SUPPORT BRACKET FOR A STAIRCASE TREAD

Donald Leslie Ward, 58 Burnham Road,
Leigh-on-Sea, Essex, England

Filed Nov. 18, 1974, Ser. No. 524,447

Claims priority, application Great Britain
May 22, 1974, Aug. 14, 1974

Term of patent 14 years

Int. Cl. D8—08

U.S. Cl. D8—235

Fig. 1.

Fig. 2.

Fig. 3.Fig. 4.FIG. 1 is a front view of a support bracket for a staircase tread showing my new design;

FIG. 2 is a side elevational view thereof;

FIG. 3 is a front elevational view of a modified form of the support bracket for a staircase tread shown in FIG. 1; and

FIG. 4 is a side elevational view of FIG. 3.

I claim:

The ornamental design for a support bracket for a staircase tread, substantially as shown and described.
